CLAIM

The ornamental design for a cover label for a camera, as shown and described.

DESCRIPTION

FIG. 1 is a front elevational view of a cover label for a camera showing our new design;

FIG. 2 is a top plan view thereof;

FIG. 3 is a bottom plan view thereof;

FIG. 4 is a left-side elevation view thereof;

FIG. 5 is a right-side elevation view thereof; and,

FIG. 6 is a perspective view thereof.

The broken line showing of the camera on FIG. 6 is for illustrative purposes only and forms no part of the claimed design.
